(57) **CLAIM**

I claim the ornamental design for a multi-media tablet holder, as shown and described.

DESCRIPTION

FIG. 1 is a front isometric top, right view of the multi-media tablet holder;

FIG. 2 is a back isometric top, right view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

1 Claim, 6 Drawing Sheets

FIG. 1

FIG. 2

FIG. 3

FIG. 4

FIG. 5

FIG. 6
